US0D1087525S

(12) United States Design Patent (10) Patent No.: US D1,087,525 S
(45) Date of Patent: * Aug. 12, 2025

(54) GARMENT

(71) Applicant: LULULEMON ATHLETICA CANADA INC., Vancouver (CA)

(72) Inventor: Yuliya Victorivna Yaremenko, Vancouver (CA)

(73) Assignee: LULULEMON ATHLETICA CANADA INC., Vancouver (CA)

() Term: 15 Years

(21) Appl. No.: 29/849,167

(22) Filed: Aug. 9, 2022

Related U.S. Application Data

(62) Division of application No. 29/748,505, filed on Aug. 29, 2020, now Pat. No. Des. 963,290.

(57) CLAIM

The ornamental design for a garment, as shown and described.

DESCRIPTION

FIG. 1 is a front view of a garment according to the design; FIG. 2 is a rear view thereof; FIG. 3 is a right side view thereof; FIG. 4 is a left side view thereof; FIG. 5 is a front perspective view thereof; FIG. 6 is a rear perspective view thereof; and, FIG. 7 is a rear view of the garment shown in an environment of use.

The portions of the garment shown in broken lines in FIGS. 1-7 do not form part of the claimed design. The broken line showing of the arms, torso, neck, and head in FIG. 7 is for the purpose of illustrating portions of the environmental structure and forms no part of the claimed design.

1 Claim, 7 Drawing Sheets
